NOZZLE UNIT FOR A VACUUM CLEANER

Erich Mittelsten Scheid, Wuppertal-Barmen, Germany

Application June 9, 1958, Serial No. 51,240

Claims priority, application Germany February 11, 1958

Term of patent 7 years

(Cl. D9—2)

FIG. 1

FIG. 2

Fig. 1 is a top perspective view of a nozzle unit for a vacuum cleaner showing my new design; and

Fig. 2 is a side view thereof.

The opposite side of the nozzle unit has the same design as the side shown in Fig. 2.

I claim:

The ornamental design for a nozzle unit for a vacuum cleaner, as shown and described.
